The ornamental design for a light fixture having planar optics, as shown and described.

DESCRIPTION

FIG. 1 is a top perspective view of a first embodiment of the light fixture having planar optics;

FIG. 2 is a bottom perspective view thereof;

FIG. 3 is a top plan view thereof;

FIG. 4 is a right side elevational view thereof;

FIG. 5 is a bottom plan view thereof;

FIG. 6 is a front elevational view thereof;

FIG. 7 is a rear elevational view thereof;

FIG. 8 is a top perspective view of a second embodiment of the light fixture having planar optics;

FIG. 9 is a top plan view thereof;

FIG. 10 is a right side elevational view thereof;

FIG. 11 is a front elevational view thereof; and,

FIG. 12 is a rear elevational view thereof.

Bottom views of the second embodiment of the light fixture having planar optics are identical to the bottom views (FIGS. 2 and 5) of the first embodiment of the light fixture having planar optics.

The left side of the light fixture having planar optics is a mirror image of the right side for both embodiments.

The broken lines shown on the drawings depict portions of the light fixture that form no part of the claimed design.
